UNITED STATES PATENT OFFICE

2,673,725

POWER-DRIVEN CUTTING MACHINE FOR
PAVEMENTS AND THE LIKENeligh C. Coates, Kansas City, Mo., assignor to
Concrete Saw Company, Kansas City, Mo., a
corporation of Missouri

Application August 21, 1950, Serial No. 180,592

5 Claims. (Cl. 262—20)

1

This invention has to do with an assembly particularly adapted to cut kerfs in road surfaces or the like, the primary object being to provide an adjustable, power driven, rotary cutting element having a mobile support so arranged as to minimize the binding of the cutter within the kerf occasioned by movement of the assembly over uneven terrain being cut.

It is the most important object of the present invention to provide a cutter for road surfaces and the like that includes a swingable cutter-head mounted on a mobile platform having a number of wheels to support the same with one of the wheel and axle assemblies swingably secured to the platform to compensate for uneven terrain and thereby reduce the amount of bind between the cutter itself and the kerf being cut, and further, for the purpose of facilitating manual handling of the apparatus as the same is pushed along or otherwise motivated and guided to cut on a straight line.

Another important object of this invention is the provision of a cutting assembly having a mobile platform, together with a frame swingable on the platform, the frame carrying a rotatable cutter and a prime mover for the latter, all movable as a unit as the frame is swung, to vary the height of the cutter blade and therefore, the depth of the slot being cut.

Other objects of this invention include the way in which the entire assembly is rendered adaptable for automatic guiding along a straight line; the way in which manually operable means is provided for the swingable cutter-head to vary the depth of the cut; and the details of construction relating not only to the above-mentioned pivotal connection between one of the wheel and axle assemblies of the support, but to the manner of adjustably mounting the auxiliary frame or cutter-head upon the platform-like support.

In the drawing:

Figure 1 is a front perspective view of a power driven cutting machine for pavements and the like, made according to the present invention.

Fig. 2 is a fragmentary, side elevational view thereof, parts being broken away and in section for clearness.

Fig. 3 is a detailed, sectional view of a portion of the manual control for the swingable cutter-head; and

Fig. 4 is an elevational view of a modified form of a wheel and axle assembly.

A suitable support for the component parts of the power driven cutting machine hereof, preferably takes the form of a flat, horizontal plat-

2

form 10, having downturned flanges 12 and supported by a pair of wheel and axle assemblies broadly designated by the numerals 14 and 16 respectively.

5 The rearmost assembly 14 includes an elongated shaft 18 passing through the side flanges of the platform 10 and having a pair of wheels 20 and 22 thereon. The forwardmost assembly 16 includes an elongated shaft 24 having wheels 26 and 28 rotatably secured thereto.

The shaft or axle 24 passes through a tube 30 that is, in turn, rigidly connected with a transverse tubular member 32 midway between the ends of the axle 24. A short stub shaft 34 secured to the lowermost face of platform 10 projects through the forwardmost flange 12 and through the tubular member 32 for rotatably mounting the latter and thereby serving as the sole means of interconnection between assembly 16 and the platform 10.

10 The platform 10 has a pair of spaced-apart upstanding bearings 36 on the uppermost face thereof for rotatably receiving a shaft 38 that spans the distance between the bearings 36. Shaft 38 intersects an elongated auxiliary frame 40 intermediate the ends of the latter and is preferably secured rigidly to the latter. The auxiliary frame 40 has a tubular housing 42 extending laterally therefrom at its normally forwardmost end for rotatably receiving a driven shaft 44 having a circular cutting disc 46 on one end thereof and a sheave 48 secured to its opposite end.

15 The frame 40 has a wedge-shaped base 50 on its uppermost face adjacent that end thereof opposite to the housing 42 and directly above the shaft 38 for an internal combustion engine 52 or other prime mover such as an electric motor. The drive shaft 54 of prime mover 52 has a pulley 56 thereon, and an endless belt or the like 58 is trained over sheave 48 and pulley 56, thereby operably connecting prime mover 52 with the rotatable cutting disc 46. By virtue of the wedge shape of base 50, the prime mover is supported in a normal upright condition when the cutter disc 46 is lowered from the position illustrated in Figs. 1 and 2 to a cutting position as hereinafter to be made more clear.

20 A pair of spaced-apart, U-shaped handle bars 60 are secured to the side flanges 12 of platform 10 and extend upwardly and rearwardly therefrom. The handle bars 60 are interconnected by a bracket 64 that, in turn, is provided with a pair of down-turned ears 66 intermediate the ends thereof, having a block 68 pivotally held therebetween by a pair of pintles 70. The block 68 is

3

internally tapped for receiving an externally-threaded, elongated rod 72 that passes through an opening 74 in the bracket 64 and has a crank arm 76 on the uppermost end thereof. The rod 72 depends from the bracket 64 and passes loosely through a perforated block 78 that is, in turn, pivotally secured between a pair of furcations extending outwardly from that end of the frame 40 opposite to disc 46, one only of such furcations being illustrated and designated by the numeral 80. Each furcation is provided with a pintle 82 for pivotally mounting the block 78 in the same manner as illustrated in Fig. 3, with respect to the block 68. Downward movement of the rod 72 with respect to block 78 is limited by means of a nut or collar 84, and a spring 86 coiled about the rod 72 is interposed between block 78 and a nut 88 on the lower-most end of rod 72.

Means for holding the rod 72 and parts associated therewith in a selected position to govern the depth of cut includes a split tube 90 circumscribing the rod 72 having a pair of spaced-apart, laterally-projecting ears 92 which receive a clamping element 94 capable of contracting the tube 90 into and out of gripping relationship to rod 72 when element 94 is tightened.

A scale 95 formed on rod 72 has indicia thereon to guide the operator in setting tube 90 for stopping engagement with block 68 when cutter 46 reaches the desired depth in response to manual manipulation of crank arm 76. The tube 90 is set to hold cutter 46 in an elevated position in Fig. 1. When a cut having a depth of two inches, for example, is to be made, the tube 90 is adjusted along rod 72 to have its lower end in register with the two inch designation on scale 95. Thus, when arm 76 has been turned to draw rod 72 upwardly, allowing cutter 46 to lower to a place where tube 90 is against block 68, the cutter cannot be lowered further; and the cut is of a depth indicated on scale 95.

An arcuate fender or guard 104 is provided on the frame 40 for the disc 46 in overlying relationship to the latter, said guard 104 having a removable section 106. Section 106 is removed when the forward or front portion of the cutter 46 is to be moved against the wall, curbing or other vertical structure.

Fluids such as liquid coolants may be directed to the cutter disc 46 through the medium of a line 108 registering with guard 104 and having a manually-operable valve 110 interposed therein and mounted on the bracket 64. An arm 96 extending forwardly from clevice 105 is supported at its outermost end by caster wheel 98, and the pointer 100 is pivotally secured thereto. An L-shaped pointer 102 is, also, pivotally carried by the platform 10 at the rearmost edge thereof as at 103.

Both pointers 100 and 102 may be swung to an inoperative position about their respective mountings when the machine is not in use. These said pointers are in alignment with cutter 46 and such distances forwardly and rearwardly therefrom as to assure accuracy of cut and a minimum amount of binding.

During normal use, the entire assembly is moved forwardly by an operator grasping the handle bars 60 and directing his weight against the arcuate surface on intermediate tie member 61. Pointers 100 and 102 are maintained on a preformed line on the surface to be cut. The depth of the cut is determined by swinging of the frame 40, together with the cutter 46 and the prime mover 52 thereon as a unit about the axis

4

of the shaft 38, which swinging movement is controlled by the rotation of rod 72 in block 68.

After the operator has lowered the cutter blade 46 from that illustrated in Figs. 1 and 2 by manipulation of crank arm 76 to a cutting position, the rod 72 is prevented from further rotation and longitudinal movement in one direction by the tube 90 which has been set as above explained. As the cutter blade 46 is caused to rotate by prime mover 52, any relatively hard obstruction within the path of travel of the cutter blade 46 tending to cause the latter to rise above its adjusted, set position will be compensated for by the sliding movement of block 78 on rod 72 against the action of spring 86.

Irrespective of the advantages of a three-point mobile support for platform 10, the four wheels 20, 22, 26 and 28 have been provided so as to facilitate the guiding of the assembly by the operator along a straight line. In other words, at all times, irrespective of the unevenness of the surface being traversed, the platform 10 and all parts mounted thereon are supported at four points; and such is made possible because of the pivotal connection between tube 30 of axle 24 and the shaft 34 of platform 10.

The apparatus is further rendered highly maneuverable by virtue of the fact that the operator may raise or lower the disc 46 while the prime mover 52 continues in operation by simply bearing downwardly upon the handle bars 60 and member 61 and pivoting the platform 10 on axle 18. In view of the fact that the wheel and axle assembly 16 is relatively close to the cutting disc 46, binding of the latter in the kerf being formed will be prevented when the wheels 26 and 28 enter a cavity or pass over a rise in the pavement being cut. Since the operator has more control over the rear wheel and axle assembly than that of the assembly 16, he can prevent such binding of the disc 46 as the same becomes necessary when one of the rear wheels rises or falls.

The machine above described may be used with a pair of tracks 112 when slightly modified as illustrated in Fig. 4 when it is desirable to positively guide the assembly in its forward movement along a straight path of travel. Tracks 112 are L-shaped in cross-section, and the horizontal flanges thereof serve as a support for the wheels of assemblies 14 and 16. Additionally, one end of each axle 18 and 24 respectively is provided with a sheave 114 that is guided along the uppermost edge of the upright flange of one of tracks 112 and which may or may not ride upon such edge, as shown in Fig. 4.

The tracks 112 may be interconnected or anchored to the pavement being cut in any suitable and well-known manner to prevent movement out of relation with the line of cut therebetween.

Having thus described the invention what is claimed as new and desired to be secured by Letters Patent is:

1. A machine for cutting pavement or the like, said machine comprising a platform; a frame; a cutter rotatably carried by the frame; a prime mover on the frame operably coupled with said cutter; means mounting the frame on the platform for swinging movement on an axis parallel with the axis of rotation of the cutter, with the cutter disposed forwardly of the platform and therebeyond; a rear wheel and axle assembly including an axle secured to said platform in parallelism with said axis of rotation and having a pair of wheels; a front wheel and axle assembly 75 including an axle normally parallel with said

axis of rotation and having a pair of wheels; a front axle support on the platform for swinging movement of the front axle with respect thereto on an axis parallel with the normal path of travel of the machine, said four wheels providing a four-point support for the machine, said rear wheels and said front axle support providing a three-point mounting for the platform, whereby to minimize binding of the cutter in the pavement as the machine is moved therealong, during cutting and when the pavement is uneven; and structure interconnecting the frame and the platform for varying the depth of cut.

2. A machine as set forth in claim 1, wherein said structure includes an extensible member extending upwardly from the frame at one end thereof remote from the cutter, and means on the platform for mounting the uppermost end of said member, said axis of swinging movement of the frame being intermediate the ends of the latter.

3. A machine as set forth in claim 2, wherein said axis of swinging movement of the frame is above the platform and said axles, in a vertical plane disposed between the axles and parallel thereto.

4. A machine as set forth in claim 1, wherein

said axis of swinging movement of the front axle is parallel to and substantially in alignment with the plane of rotation of the cutter.

5. A machine as set forth in claim 4, wherein said axis of swinging movement of the front axle is intermediate between the wheels of the front assembly.
